W. SCHUMAKER,
HAYRACK FASTENER,
APPLICATION FILED MAY 27, 1922.

1,432,914.

Patented Oct. 24, 1922

UNITED STATES PATENT OFFICE.

WILLIAM SCHUMAKER, OF MINNESOTA LAKE, MINNESOTA.

HAYRACK FASTENER.

Application filed May 27, 1922. Serial No. 564,053.

To all whom it may concern:

Be it known that WILLIAM SCHUMAKER, a citizen of the United States, residing at Minnesota Lake, in the county of Faribault 5 and State of Minnesota, has invented certain new and useful Improvements in Hayrack Fasteners, of which the following is a specification, reference being had to the accompanying drawings.

10 This invention relates to a hay rack fastener and it is an object of the invention to provide a device of this general character having novel and improved means whereby the same may be effectively employed for the 15 purposes desired.

Another object of the invention is to provide a device of this general character having novel and improved means whereby the same may be readily applied in working 20 position and which operates in a manner to tightly hold or clamp the rack or a portion thereof to a side rail or board of a wagon body or the like.

The invention consists in the details of 25 construction and in the combination and arrangement of the several parts of my improved hay rack fastener whereby certain important advantages are attained and the device rendered simpler, less expensive and 30 otherwise more convenient and advantageous for use, as will be hereinafter more fully set forth.

The novel features of my invention will hereinafter be definitely claimed.

35 In order that my invention may be the better understood, I will now proceed to describe the same with reference to the accompanying drawings, wherein:

Figure 1 is a fragmentary view in perspective of a hay rack fastener constructed 40 in accordance with an embodiment of my invention;

Figure 2 is a view in front elevation of the structure as illustrated in Figure 1;

45 Figure 3 is a view partly in section and partly in elevation of the structure as herein disclosed;

Figure 4 is a view in perspective of one of the members comprised in my improved fastener, a portion being broken away; and

50 Figure 5 is a view in perspective of the second member comprised in my improved fastener as herein set forth.

As disclosed in the accompanying drawings, 55 1 denotes a fragmentary portion of a

side rail or board of a wagon body resting upon a transversely disposed sill or beam 2. 3 denotes a fragmentary portion of a bottom or transverse member of a hay rack.

My improved fastener comprises two 60 members A and B which co-act in a manner to provide an effective connection between the wagon body and the rack.

The member A comprises an elongated flat plate 4 of a length substantially equal to 65 the width of the side rail or board 1 and has close contact with the outer face of said board or rail 1 when in applied position. The plate 4 is provided with longitudinally spaced openings 5 through which suitable 70 fastening means may be disposed for holding the plate 4 to the rail or board 1.

One end portion of the plate 4 is continued by a shank or stem 6 which is adapted to be directed through the sill 2 and upon 75 the outer or free end portion of the shank or stem 6 is a clamping nut 7 which engages the sill 2 from below and whereby the said rail or board 1 is effectively maintained in applied position relative to the sill 2. 80

The lower longitudinal marginal portions of the plate 4 are defined by the outstanding flanges 8 and pivotally engaged with the upper portion of one of said flanges 8 is a swinging latch or holding member 9, which, 85 when disposed across the space between the flanges 8, is engaged with the spring catch 10 carried by the second flange 8.

The upper portion of the plate 4 is transversely enlarged as at 11 and the side and 90 top edges of said enlarged portion 11 are defined by the outstanding flanges 12, the top flange having its outer edge defined by the depending flange 13.

The member B comprises an elongated 95 arm 14 provided at one end portion with a head 15, a marginal portion of the top or outer surface of the head 15 being defined by an outstanding flange 16 which is adapted to engage rearwardly of the flange 12 when 100 the members A and B are in locking relation. When the members A and B are in locking relation the member B overlies the member A with the flange 15, as just stated, engaged behind the flange 12 and the arm 105 14 positioned between the flanges 8 of the plate 4. The catch 9 is then swung across the space between the flanges 8 and over the arm 14 whereby the members A and B are effectively held against separation but in a 110

manner whereby the member B may be moved outwardly to effect a release of the hay rack when desired.

Pivots engaged with the opposite side 5 faces of the head 15 through the instrumentality of the bolt or pivot member 16^a are the elongated arms 17. The arms 17 are provided with longitudinally disposed slots 18 through which are disposed from within 10 the headed shanks or bolts 19. The shanks or bolts 19 are also disposed through the side arms 20 of the U-shaped member 21, said arms 20 overlying the arms 17. Engaged with each of the shanks or bolts 19 and co- 15 acting with an arm 20 of the member 21 is a clamping nut 22. By this means the member 21 may be adjusted lengthwise of the arms 17 as the occasions of practice may require and be effectively maintained in such 20 adjustment.

Before the member B is operatively engaged with the member A the transverse beam 3 of the rack is disposed between the arms 17 and the arms 20 of the member 21 25 with the intermediate portion of the member 21 above the beam 3. The member 21 is then adjusted lengthwise of the arm 17 to cause the intermediate portion of said member to have proper contact with the top 30 face of the beam 3 when the members A and B are in relative locking engagement.

From the foregoing description it is thought to be obvious that a hay rack fastener constructed in accordance with my invention is particularly well adapted for use 35 by reason of the convenience and facility with which it may be assembled and operated, and it will also be obvious that my invention is susceptible of some change and 40 modification without departing from the principles and spirit thereof and for this reason I do not wish to be understood as limiting myself to the precise arrangement and formation of the several parts herein 45 shown in carrying out my invention in practice except as hereinafter claimed.

I claim:

1. A fastening device of the class described comprising a plate provided with 50 parallel spaced flanges and having an outstanding flange provided with an inwardly disposed flange, a member provided with a head, said head having a flange to engage inwardly of the depending flange of the plate, a portion of said member being received between the flanges of the plate when 55 the flange of the member is engaged inwardly of the depending flange of the plate, means for holding said member between the

parallel flanges, and a work engaging member carried by the head of the member. 60

2. A fastening device of the class described comprising a plate provided with parallel spaced flanges and having an outstanding flange provided with an inwardly disposed flange, a member provided with a head, said head having a flange to engage inwardly of the depending flange of the plate, a portion of said member being received between the flanges of the plate when 70 the flange of the member is engaged inwardly of the depending flange of the plate, means carried by the parallel flanges for holding said member between the parallel flanges, and a work engaging member carried by the head of the member. 75

3. A fastening device of the class described comprising a plate provided with parallel spaced flanges and having an outstanding flange provided with an inwardly disposed flange, a member provided with a head, said head having a flange to engage inwardly of the depending flange of the plate, a portion of said member being received between the flanges of the plate when 80 the flange of the member is engaged inwardly of the depending flange of the plate, a swinging latch carried by one of the parallel flanges and of a length to bridge the 85 space between the flanges to hold a member between the parallel flanges, a catch carried by the second parallel flange to engage the latch, and a work engaging member carried by the head of the member. 90

4. A device of the class described comprising two separable members having co-acting means for connecting the same, spaced arms pivotally engaged to one of said members, a member substantially in the form of an inverted U having its side arms overlying the first named arms, and means for connecting the side arms of the inverted U-shaped member and the first named arm. 100

5. A device of the class described comprising two separable members having co-acting means for connecting the same, spaced arms pivotally engaged to one of said members, a member substantially in the form of an inverted U having its side 105 arms overlying the first named arms, means for connecting the side arms to the inverted U-shaped member and the first named arm, said U-shaped member being relatively adjustable longitudinally of the first named 110 arms. 115

In testimony whereof I hereunto affix my signature.

WILLIAM SCHUMAKER.
